UNITED STATES PATENT OFFICE

2,665,551

HYDRAULIC PUMPING UNIT

Roy L. Chenault, Seneca, Pa., assignor to United States Steel Corporation, a corporation of New Jersey

Application December 20, 1950, Serial No. 201,786

6 Claims. (Cl. 60—51)

1

This invention relates to improvements in hydraulic pumping units for operating subsurface oil well pumps.

I am aware that many designs of such units exist and have been patented, but those with which I am familiar have disadvantages that have limited their adoption and use. Fundamentally these units comprise a hydraulic cylinder, which contains a reciprocable ram connected in some way to a sucker rod string, a motivating pump for applying hydraulic pressure to the cylinder and thus reciprocating said ram, a valve arrangement for controlling the direction in which such pressure is applied and thus controlling reversals of the ram, and a counterbalance for equalizing the load on the motivating pump during upstrokes and downstrokes of the ram. A suitable prime mover drives the motivating pump. In most instances positive displacement motivating pumps have been preferred, but such pumps deliver fluid continuously and have necessitated complicated by-pass arrangements for fluid delivered while the ram decelerates and reverses at the ends of its strokes. The counterbalance preferably is pneumatic, but previous units have failed to utilize this counterbalance as a means for cushioning the ram, but only for storing energy on the downstroke to assist in the upstroke. In most previous units the ram has moved at the same speed during both its upstroke and its downstroke, whereas advantageously the ram could move much faster during its downstroke.

Centrifugal pumps and reversible variable volume pumps also have been used as motivating pumps and have overcome some of these difficulties, but introduce others. A centrifugal pump allows slippage during deceleration and reversals of the ram, and thus enables the controls to be simplified, but such slippage causes a power loss and unduly heats the hydraulic fluid. A reversible variable volume pump reduces its delivery to decelerate and reverse the ram and it allows for different speeds in the two strokes. However, such pumps are complicated and costly and they produce a widely fluctuating load on their prime mover.

An object of the present invention is to provide improved hydraulic pumping units which overcome the foregoing disadvantages; that is, which employ positive displacement pumps and yet do not require a complicated by-pass, which utilize their pneumatic counterbalance for cushioning the ram, and in which the ram can move faster during its downstroke than during its upstroke.

2

A further object of the invention is to provide improved hydraulic pumping units which are capable of absorbing energy continuously from a prime mover and of utilizing this energy efficiently for operating the ram without necessity for by-passing any hydraulic fluid nor decreasing the rate of energy absorption at the extremes of the ram stroke.

10 A further object of the invention is to provide improved hydraulic pumping units which employ a positive displacement motivating pump and which have two pneumatic counterbalance tanks, the first of said tanks furnishing pressure which cushions the ram during its downstroke and supercharges the pump during the upstroke of the ram, the second of said tanks furnishing pressure which directly assists the motivating pump during the upstroke of the ram and receiving the pump output and storing its energy during the 20 downstroke.

In accomplishing these and other objects of the invention, I have provided improved details of structure, preferred forms of which are shown in the accompanying drawings, in which:

25 Figure 1 is a schematic vertical sectional view of a hydraulic pumping unit embodying features of the present invention, the parts being shown in the positions they occupy for a downstroke of the ram;

30 Figure 2 is a view similar to Figure 1, but showing the parts in their upstroke positions;

Figure 3 is a schematic vertical sectional view of a unit of the present invention, but having the valves and other details of modified construction, the parts being shown in their downstroke 35 positions; and

Figure 4 is a schematic vertical sectional view which shows the valves of Figure 3 in their upstroke positions, other details being illustrated as 40 in Figures 1 and 2 for simplicity.

The hydraulic pumping unit shown in Figures 1 and 2 comprises a lifting cylinder 10, a ram 12 reciprocable up and down in said cylinder, a motivating pump 13, a main valve 14, a pilot valve 15, a first counterbalance tank 16, and a second counterbalance tank 17. A polished rod 18 is connected to ram 12 and a sucker rod string, not shown, is connected to said polished rod and extends into a well casing 19. This rod string operates a subsurface pump, not shown. The motivating pump 13 is a positive displacement pump of any standard or desirable construction and it delivers hydraulic fluid continuously at substantially constant volume and pressure. This pump is driven from any suitable prime mover, not shown.

3

Main valve 14 includes a housing 20 which has three ports 21, 22 and 23 and which contains a reciprocable valve spool 24 having upper and lower lands 24a and 24b. A pipe 25 connects port 21 with a port 26 in the lower end of the lifting cylinder 10. A pipe 27 connects port 22 with the inlet side of the motivating pump 13. A pipe 28 connects port 23 with the discharge side of said motivating pump. A pipe 29 connects pipe 27 and the lower end of the first counterbalance tank 16 and contains a throttle valve 30. A pipe 31 connects pipe 28 and the lower end of the second counterbalance tank 17.

The main valve has an operating cylinder 32 which contains a reciprocable piston 33. A piston rod 34 connects piston 33 and the main valve spool 24. A spring 35 surrounds said piston rod and tends to move the piston, piston rod and valve spool to their upper position shown in Figure 1.

A suitable hydraulic fluid fills the lower part of cylinder 10, pipes 25, 27, 28, 29 and 31, the central part of the main valve cylinder between lands 24a and 24b, and the lower part of counterbalance tanks 16 and 17. The upper parts of these tanks contain compressed air, which initially is supplied from an air compressor 36 and piping 37. This piping contains a pressure regulator 38 which maintains a slightly lower pressure in tank 16 than in tank 17. Preferably the tanks have relief valves 39 and 40. The air compressor, pressure regulator and relief valves can be of any standard or desirable construction and hence are not shown in detail. The two tanks are of unequal volume, tank 16 being the larger, as hereinafter explained.

The lower end of the main valve housing 20 carries an air make-up pump 41, the purpose of which is to replenish automatically air lost from the counterbalance tanks 16 and 17 through leakage without necessitating operation of compressor 36. This pump includes a cylinder 42, which is fixed to the lower end of said housing, and a plunger 43, which is fixed to the lower face of the main valve spool 24 and thus reciprocates in said cylinder as said valve spool moves up and down. The cylinder has an intake port 44 and a check valve 45 which acts as a discharge port. A pipe 47 connects said discharge port and one of the counterbalance tanks, in this instance 17. On the upstroke of the main valve spool, plunger 43 draws air into cylinder 42 via intake port 44. On the downstroke the plunger forces such air through check valve 45 and pipe 47 into the counterbalance tank.

An adjustable unloading valve 48 is connected between the intake port 44 and pipe 47. Said unloading valve includes a plunger 49 and a spring 50. Normally said spring moves said plunger to a position in which it allows air to enter the intake port. Whenever pressure in the counterbalance tank is sufficient to overcome compression in the spring, it moves the plunger to a position in which it closes the intake port. The pump then ceases to add air to the counterbalance tanks until the pressure drops enough that spring 50 returns the plunger to its normal position. The compression in the spring is adjustable to adjust the pressure maintained in the tanks.

Cylinder 10 has a port 51 in its upper end above ram 12. A low pressure scavenger pipe 52 connects this port with the lower end of one of the counterbalance tanks 16 or 17, in this instance 16. Said pipe contains a small scavenger pump 53 of any standard or desirable construc-

tion. A pipe 54 connects the lower end of the main valve operating cylinder 32 to said scavenger pipe and has branches 54a and 54b connected to the upper and lower ends of the main valve housing 20. The scavenger system returns to the counterbalance tank any fluid which leaks past the ram or the main valve operating piston or the main valve spool. Said system also returns fluid discharged from pilot valve 15, as hereinafter explained.

Pilot valve 15 includes a housing 55 which has five ports 56, 57, 58, 59 and 60 and which contains a reciprocable valve spool 61 having left and right lands 61a and 61b. A pipe 62 connects port 56 and scavenger pipe 52. Cylinder 10 has a port 63 in its extreme lower end and a port 64 somewhat above its port 26. A pipe 65 connects port 63 with both ports 57 and 59 in the pilot valve housing. A pipe 66 connects ports 60 and 64. A pipe 67 connects port 58 with a port 68 in the upper end of the main valve operating cylinder 32.

The pilot valve has an operating cylinder 69 which has ports 70 and 71 and contains a reciprocable plunger 72. Cylinder 10 has a port 73 in its upper portion. A pipe 74 connects ports 73 and 70. A pipe 75 connects port 71 with pipe 62, which extends to the scavenger pipe 52. Plunger 72 has a stem 76 which extends into the pilot valve housing 55 and is adapted to abut the left end of pilot valve spool 61. A spring 77 surrounds stem 76 and tends to move the plunger and stem to the left away from the pilot valve spool.

Figure 1 shows the position of the parts as the ram makes a downstroke. Ram 12 is moving downwardly gravitationally under the weight of the rod string and is situated between ports 73 and 64 of cylinder 10. The space in the pilot valve operating cylinder 69 behind or to the left of plunger 72 is relieved via port 70, pipe 74, port 73, the upper part of cylinder 10 and port 51 to scavenger pipe 52. Therefore spring 77 has moved plunger 72 all the way to the left. Pilot valve spool 61 has moved all the way to the right, the means for thus moving it being hereinafter described. The left end of land 61a is subjected to pressure from cylinder 10 transmitted via port 64, pipe 66 and port 60. The right end of land 61b is subjected to the same pressure transmitted via port 63, pipe 65 and port 57, so that the spool does not tend to move in either direction. Land 61a blocks port 59 and the spool establishes communication between ports 56 and 58. Therefore the space in the main valve operating cylinder 32 above piston 33 is relieved via port 68, pipe 67, port 58, pilot valve cylinder 55, port 56, and pipe 62 to scavenger pipe 52. Spring 35 has moved piston 33, piston rod 34, main valve spool 24 and plunger 43 to their upper position. Land 24b of the main valve spool blocks port 23 and the spool establishes communication between ports 21 and 22.

Descent of ram 12 forces hydraulic fluid from cylinder 10 through port 26, pipe 25, port 21, main valve cylinder 20, and port 22, into pipe 27. Part of this fluid flows through pipe 29 and throttle valve 30 into counterbalance tank 16, and part flows into the inlet of the motivating pump 13, which pumps it via pipes 28 and 31 into tank 17. Thus the air pressure in tank 16 effectively cushions the ram as it descends, and the output of the motivating pump goes to tank 17 where it stores energy to be used later as the pump 13 raises the ram. The adjustment in the

opening of throttle valve 30 controls the rate of descent of the ram, which can be quite rapid. As the ram approaches its reversal point at the end of its downstroke, it passes port 64 in cylinder 10, whereupon the space in pilot valve cylinder 55 to the left of land 61a is relieved to the scavenger pipe 52. Pressure on the right end of land 61b moves spool 61 to the left until its left end abuts the end of stem 76. Land 61b now blocks port 56 and the spool establishes communication between ports 58 and 59. The top of the main valve operating piston is subjected to the pressure of the fluid in cylinder 10 transmitted via port 63, pipe 65, port 59, pilot valve cylinder 55, port 58, pipe 67 and port 68. The main valve operating piston, piston rod and spool and plunger 43 commence to descend against the action of spring 35. The parts are adjusted so that the ram completes its downstroke at the same time the main valve spool reaches its lower position.

Figure 2 shows the position of the parts as the ram makes an upstroke. The ram again is situated between ports 64 and 73 of cylinder 10. As the ram moved past port 64, it admitted pressure to the space in pilot valve cylinder 55 to the left of land 61a, but spool 61 did not move since the pressure in the space on the right of land 61b balanced this pressure on the left. Land 24a of the main valve spool blocks port 22 in the main valve housing and the spool establishes communication between ports 21 and 23.

The fluid from tank 16 now flows to the inlet of the motivating pump 13 and the pressure in this tank supercharges the pump. The fluid discharged from the motivating pump joins fluid forced from tank 17 by the air pressure built up therein, and such fluid flows through the main valve housing, port 21, pipe 25, and port 26 to raise the ram. The ascent of the ram is much slower than its descent.

As the ram approaches the top of its upstroke, it passes port 73 in cylinder 10, whereupon the space in the pilot valve operating cylinder 69 to the left of its plunger 72 is subjected to the pressure of the fluid in cylinder 10. Such pressure moves the plunger to the right against the action of spring 77 and the pressure on the right end of the plunger applied to a smaller area. The plunger pushes the pilot valve spool 61 to the right and thus moves the parts to the position for another downstroke. When ram 12 passes port 73 on the next downstroke, the parts have returned fully to the position shown in Figure 1.

Preferably cylinder 10 and ram 12 are equipped with dashpots to cushion the ram additionally at the ends of its strokes. Numerous arrangements are possible, but at the top I have shown a boss 78 which projects downwardly from the end of the cylinder and a recess 79 in the upper face of the ram. At the bottom I have shown an annular wall 80 upstanding from the bottom of the cylinder and a boss 81 extending downwardly from the underside of the ram. In accordance with known principles, both dashpots have outlet means which decrease in area as the boss enters the recess, such as the V-slot 82 shown in the annular wall 80.

One of the hazards of operating pumping units is that sucker rod strings can break. The pumping unit preferably is equipped with means for closing off the pressure on the ram when there is a sudden release of load caused by such breakage. Otherwise the pressure from the

counterbalance tanks and the motivating pump could drive the ram to the top of the cylinder with a destructive force. This means includes a flow control valve 83 and a restrictive orifice 84 in pipe 25. Said valve has an operating diaphragm 85 situated in a chamber 86. A pipe 87 connects the space in chamber 86 above diaphragm 85 with pipe 25 to the right of orifice 84. A pipe 88 connects the space in the chamber below the diaphragm with pipe 25 to the left of the orifice.

During the upstroke of the ram when the rod string is subjected to the greatest stress, hydraulic fluid flows through pipe 25 from right to left so that the pressure to the right of orifice 84 is slightly greater than the pressure to the left. Therefore the pressure pushing down on diaphragm 85 and tending to close valve 83 is slightly greater than the pressure pushing up on said diaphragm and tending to open the valve. A spring 89 pushes up on the diaphragm, and at normal flowage through pipe 25 balances this pressure differential so that valve 83 stays fully open. If there is a sudden surge of fluid through pipe 25 caused by a sudden release of load on the ram, the pressure differential across the orifice increases, overcomes the force of spring 89 and partially closes the valve, and the ram moves slowly to the top of its cylinder.

Preferably the unit also is equipped with a pressure switch 90 for stopping its operation when the pressure differential between the inlet and discharge sides of the motivating pump 13 becomes too high. This switch is situated in a by-pass line 91, which is connected to pipes 27 and 28 on opposite sides of the pump. This by-pass line serves merely to transmit pressures to the switch; there is no actual flow of hydraulic fluid through it. When the pressure on the discharge side of the pump becomes abnormally high, as for example when valve 83 closes, the pressure switch operates and stops the prime mover.

As previously mentioned, counterbalance tank 16 is of larger volume than counterbalance tank 17. The optimum proportions of the volumes of the two tanks are determined by the ratio of the time required for a downstroke to that required for an upstroke. For example, if the upstroke requires twice as much time as the downstroke, tank 16 should have twice the volume of tank 17. Then two-thirds of the hydraulic fluid which flows from cylinder 10 during a downstroke flows to tank 16 and one-third is pumped into tank 17 by the motivating pump 13. This arrangement insures that the levels of hydraulic fluid and the air pressures in the two tanks increase by the same amount during each downstroke.

Figure 3 shows a pumping unit which has several modifications, any of which can be incorporated individually in the pumping unit shown in Figures 1 and 2. These modifications are: (a) a simplified main valve which eliminates the operating piston and cylinder, but requires a slightly more complex pilot valve; (b) a more sensitive flow control valve; (c) the addition of an auxiliary cushioning tank which cushions the ram during the interval at the end of its downstroke while it still is descending and the main valve spool is blocking port 22; (d) the addition of an alternate outlet pipe from the first counterbalance tank 16; (e) the addition of adjustable connections between the lifting cylinder and the pilot valve, and (f) the addition of adjustable

means in the outlet from the dashpot at the bottom of the lifting cylinder. Except for these modifications, the pumping unit is the same as the unit already described, and the same reference characters identify the parts which are the same.

The modified main valve includes a housing 92 and a spool 93, which has two lands 93a and 93b that also function as operating pistons. The housing has ports 21, 22 and 23 similar to the same ports in the embodiment shown in Figures 1 and 2 and similarly connected to the motivating pump 13 and lifting cylinder 10. The housing also has control ports 94 and 95 in its upper and lower ends respectively. Pressure is admitted to the control port 95 to raise the spool to produce a downstroke of the ram and to the control port 94 to lower the spool to produce an upstroke of the ram. In each instance the opposite control port is relieved.

The modified pilot valve includes a housing 96 which has eight ports 97, 98, 99, 100, 101, 102, 103 and 104 and which contains a reciprocable spool 105. Said spool has three lands 105a, 105b and 105c. Ports 101 and 104 at the ends of the housing are connected to the lifting cylinder for controlling shifting of the spool in the same fashion as the corresponding ports 57 and 60 in the embodiment shown in Figures 1 and 2. The modified pilot valve also has the same operating piston and cylinder as this other embodiment. A pipe 106 connects both ports 97 and 100 with pipe 27, which extends between the main valve and the inlet of the motivating pump 13. A pipe 107 connects both ports 98 and 99 with pipe 28, which extends between the main valve and the discharge of said motivating pump. A pipe 108 connects port 102 with the upper control port 94 of the main valve, and similarly a pipe 109 connects port 103 with the lower control port 95 thereof.

Figure 3 shows the main valve and the pilot valve in the positions their spools occupy for a downstroke of the ram. The pilot valve spool is at the right. The pilot valve admits hydraulic fluid under pressure from the motivating pump discharge to the space in the main valve housing below land 93b of spool 93. The path of flow is via pipes 28 and 107, ports 98 and 103, pipe 109 and port 95. The pilot valve also relieves the space above land 93a of the main valve spool via port 94, pipe 108, ports 102 and 100, and pipes 106 and 27 to the inlet of the motivating pump. Therefore the main valve spool remains in its upper position.

Figure 4 shows the modified main valve and pilot valve in the positions their spools occupy for an upstroke. The pilot valve spool changes its position in the same fashion as in the embodiment shown in Figures 1 and 2, so that there is no need to repeat this description. The pilot valve spool now is at the left. The pilot valve admits fluid under pressure from the motivating pump discharge to the space in the main valve housing above land 93a of spool 93. The path of flow is via pipes 28 and 107, ports 99 and 102, pipe 108 and port 94. The pilot valve also relieves the space below land 93b of the main valve spool via port 95, pipe 109, ports 103 and 97, and pipes 106 and 27 to the inlet of the motivating pump. Therefore the main valve spool remains in its lower position.

The modified flow control valve differs from that shown in Figures 1 and 2 in that its restrictive orifice 84a is situated between the valve and

the lifting cylinder 10. Therefore the restrictive effect of the valve combines with that of the orifice to produce a greater pressure differential between opposite faces of the diaphragm, and causes an immediate closing of the valve when there is any undue increase in the rate of flow.

The modified unit includes an auxiliary tank 110 which is shown in Figure 3 only. This tank is connected to pipe 25 via an adjustable throttling valve 112 and to the counterbalance tank 16 via a pipe 113. The latter pipe contains a check valve 114 which admits air from the counterbalance tank to the auxiliary tank, but not the reverse. The auxiliary tank carries volume adjustment chambers 115 and 115a, which are connected to it through adjustable valves 116 and 116a. Valves 116 and 116a can be opened or closed to adjust the effective volume of the auxiliary tank as desired. The lower part of the auxiliary tank contains hydraulic fluid and the upper part compressed air. The latter enters through pipe 113 and check valve 114 and its pressure always is at least as great as that in counterbalance tank 16. It is seen that when the main valve 20 spool 93 moves downwardly at the bottom reversal of the ram, its land 93a momentarily blocks port 22 while the ram still is descending. Blocking this port cuts off counterbalance tank 16 from the ram, but now the auxiliary tank 110 furnishes sufficient cushioning effect to decelerate the ram smoothly. The throttling valve 112 can be adjusted to control this cushioning effect. During the upstroke the accumulated pressure in the auxiliary tank further assists the motivating 25 pump in raising the ram.

The modified unit has an alternate outlet pipe 117, which also is shown in Figure 3 only. This pipe extends from the first counterbalance tank 16 to pipe 27 and contains a check valve 118. 30 During the downstroke this check valve closes and all flow into the counterbalance tank is via throttling valve 30, as in the embodiment shown in Figures 1 and 2. During the upstroke the alternate outlet pipe and check valve permit a substantially unrestricted flow of fluid from counterbalance tank 16 to the inlet of the motivating 35 pump 13.

In addition to the regular ports 64 and 73 in the lifting cylinder 10, to which pipes 66 and 74 leading to the pilot valve are connected, the modified unit can have auxiliary ports 119 and 120, which are shown in Figure 3 only. Pipes 66 and 74 also are connected to these auxiliary ports, and are valved at their connections to each port. By 40 proper adjustment of the valves, the reversal points of the ram can be varied as desired.

The annular wall 80 at the bottom of the lifting cylinder 10 has two valved outlet pipes 121 and 122 which are shown in Figure 3 only. These 45 pipes join and extend up to a higher point in said cylinder. The valves in these pipes furnish a means for adjusting the flow from inside the dashpot and thereby further controlling the cushioning at the bottom of the downstroke.

From the foregoing description it is seen that the present invention furnishes a relatively simple hydraulic pumping unit which effectively overcomes the difficulties of previous units. The unit employs the more desirable positive displacement type of motivating pump, and yet requires no by-pass and it utilizes the pump output efficiently at all times. The counterbalance tanks effectively cushion the ram, as well as storing energy. The basic unit shown in Figures 1 and 2 is 50 fully effective in these respects, but any of the

refinements embodied in the modified unit shown in Figures 3 and 4 can be incorporated as desired.

While I have shown and described certain preferred embodiments of the invention, it is apparent that modifications may arise. Therefore, I do not wish to be limited to the disclosure set forth but only by the scope of the appended claims.

I claim:

1. A hydraulic pumping unit comprising a lifting cylinder, a ram mounted for up and down movement in said cylinder and adapted to be connected to a sucker rod string, a positive displacement motivating pump having an inlet and a discharge, a main valve, piping connecting said inlet and discharge with said main valve and said main valve with the lower portion of said cylinder and adapted to contain hydraulic fluid, a pilot valve for shifting said main valve and thus alternately establishing communication between said pump discharge and said cylinder for admitting hydraulic fluid to the latter for raising said ram, and establishing communication between said cylinder and said pump inlet for allowing said ram to descend gravitationally at a faster rate than said pump raises it, a first counterbalance tank connected to said piping between said main valve and said pump inlet, a second counterbalance tank of smaller volume than said first tank connected to said piping between said pump discharge and said main valve, the volumes of said tanks being in substantially the same ratio as the speed of the ram on its descent and its ascent said tanks being adapted to contain hydraulic fluid and compressed air, said first tank receiving hydraulic fluid from said cylinder and cushioning said ram as it descends and supercharging said pump as it raises the ram, said second tank receiving fluid from said pump and storing its energy as the ram descends and assisting said pump in raising the ram, and means controlling the rate at which fluid can flow into said first tank for controlling the rate of descent of said ram.

2. A hydraulic pumping unit comprising a lifting cylinder, a ram mounted for up and down movement in said cylinder and adapted to be connected to a sucker rod string, a positive displacement motivating pump having an inlet and a discharge, valve means, piping connecting said inlet and discharge with said valve means and said valve means with said cylinder and adapted to contain hydraulic fluid, said valve means alternately establishing communication between said pump discharge and said cylinder for admitting fluid to the latter for raising said ram, and establishing communication between said cylinder and said pump inlet for allowing said ram to descend gravitationally at a faster rate than said pump raises it, a first counterbalance tank connected to said piping between said valve means and said pump inlet, a second counterbalance tank connected to said piping between said pump discharge and said valve means, said tanks being adapted to contain hydraulic fluid and compressed air, said first tank receiving hydraulic fluid from said cylinder and cushioning said ram as it descends and supercharging said pump as it raises the ram, said second tank receiving fluid from said pump and storing its energy as the ram descends and assisting said pump in raising the ram, a throttle valve between said piping and said first tank for controlling the rate at which fluid can flow into said first tank for

controlling the rate of descent of said ram, alternate outlet means from said first tank to said piping to allow substantially unrestricted flow therefrom to said pump while the tank supercharges the pump, and a check valve in said alternate outlet means.

3. A hydraulic pumping unit comprising a lifting cylinder, a ram mounted for up and down movement in said cylinder and adapted to be connected to a sucker rod string, a positive displacement motivating pump having an inlet and a discharge, a main valve, piping connecting said inlet and discharge with said main valve and said main valve with the lower portion of said cylinder and adapted to contain hydraulic fluid, a pilot valve connected with said cylinder and said main valve for operation when said ram is near the ends of its strokes for shifting said main valve, whereby the latter alternately establishes communication between said pump discharge and said cylinder for raising said ram and between said cylinder and said pump inlet for allowing said ram to descend gravitationally at a faster rate than said pump raises it, a first counterbalance tank connected to said piping between said main valve and said pump inlet, a second counterbalance tank of smaller volume than said first tank connected to said piping between said pump discharge and said main valve, the volumes of said tanks being in substantially the same ratio as the speed of the ram on its descent and its ascent, said tanks being adapted to contain hydraulic fluid and compressed air, the hydraulic fluid from said cylinder on descent of said ram discharging via said main valve and dividing between said first tank and said pump inlet in substantially the same ratio as the volumetric ratio of said tanks, said first tank cushioning said ram as it descends and supercharging said pump as it raises the ram, said second tank receiving fluid from said pump and storing its energy as the ram descends and assisting said pump in raising the ram, and a throttle valve between said piping and said first tank for controlling the rate of descent of the ram.

4. A hydraulic pumping unit comprising a lifting cylinder, a ram mounted for up and down movement in said cylinder and adapted to be connected to a sucker rod string, a motivating pump having an inlet and a discharge, a main valve, piping connecting both said inlet and said discharge with said main valve and said main valve with the lower portion of said cylinder and adapted to contain hydraulic fluid, means for shifting said main valve when said ram approaches the ends of its strokes whereby this valve alternately establishes communication between said pump discharge and said cylinder for raising said ram, and between said cylinder and said pump inlet for allowing said ram to descend gravitationally at a rate faster than said pump raises it, and a pair of counterbalance tanks connected to the piping on opposite sides of said pump, the tank on the inlet side being of greater volume than that on the discharge side and the volumetric ratio of the two tanks being substantially equivalent to the speed ratio of the ram on its downstroke and upstroke.

5. A hydraulic pumping unit comprising a lifting cylinder, a ram mounted for up and down movement in said cylinder and adapted to be connected to a sucker rod string, a motivating pump having an inlet and a discharge, a main valve, piping connecting both said inlet and said discharge with said main valve and said main

valve with the lower portion of said cylinder and adapted to contain hydraulic fluid, means for shifting said main valve when said ram approaches the ends of its strokes whereby this valve alternately establishes communication between said pump discharge and said cylinder for raising said ram and between said cylinder and said pump inlet for allowing said ram to descend gravitationally at a rate faster than said pump raises it, a counterbalance tank connected to said piping on the inlet side of said pump adapted to deliver fluid to said pump on the upstroke of the ram and to receive fluid from said cylinder on the downstroke, a second counterbalance tank connected to said piping on the discharge side of said pump adapted to deliver fluid to said cylinder via said main valve on the upstroke and to receive fluid from the pump discharge on the downstroke, and means for dividing the fluid discharged from said cylinder on the downstroke between said first named counterbalance tank and the inlet of said pump in the same volumetric

ratio as the speed ratio of the ram on its down-stroke and upstroke.

6. A pumping unit as defined in claim 5 in which the means which divides the fluid between said first named counterbalance tank and the inlet of said pump includes a valve for adjusting the opening to the counterbalance tank.

ROY L. CHENAULT.
